COMBINED WASH-BASIN AND CABINET

Gustav Koenig, Christian Franz, and Peter Huebner, Bonlanden, near Stuttgart, Germany, assignors to Gustav Koenig, Unternehmensberatung, Bonlanden, near Stuttgart, Germany

Filed July 21, 1970, Ser. No. 24,049

Claims priority, application Germany Jan. 22, 1970

Term of patent 14 years

Int. Cl. D23—02

U.S. Cl. D23—59

FIG. 1

FIG. 1 is a front elevational view of a combined wash-basin and cabinet showing our new design;

FIG. 2 is a side elevational view thereof;

FIG. 3 is a top plan view thereof; and

FIG. 4 is a bottom plan view thereof.

The rear view of this combined wash-basin and cabinet, not shown in the drawings, is substantially plain and includes only the necessary openings for plumbing connections.

We claim:

The ornamental design for a combined wash-basin and cabinet, substantially as shown and described.
